US00D573034S

(12) **United States Design Patent**
Py et al.

(10) **Patent No.:** US D573,034 S
(45) **Date of Patent:** ** Jul. 15, 2008

(54) **DISPENSING CONTAINER**

(75) Inventors: **Daniel Py**, Larchmont, NY (US); **Julian V. Chan**, Spring Valley, NY (US); **Stephanie Ferreira**, Bridgeport, CT (US); **Giovanni Rodriguez**, Stamford, CT (US); **Luz Gladys Valencia**, Stamford, CT (US)

(52) **U.S. Cl. D9/686; D9/688; D9/689**

CLAIM

(58) **Field of Classification Search D2/452, D2/502–504, 522–529, 549, 682, 686–692; D28/73, 76**

(57)

See application file for complete search history.

DESCRIPTION(56) **References Cited**

FIG. 1 is a side elevational view of a dispensing container showing our new design;

U.S. PATENT DOCUMENTS

FIG. 2 is a side elevational view thereof rotated 180 degrees;

1,471,091 A	10/1923	Bessesen
2,128,035 A	8/1938	Boetel
3,412,910 A	11/1968	Hahn
3,648,903 A	3/1972	Marchant
3,662,753 A	5/1972	Tassell
3,669,323 A	6/1972	Harker et al.
3,699,961 A	10/1972	Szpur
3,756,729 A	9/1973	Tufts
3,993,069 A	11/1976	Buckles et al.
4,002,516 A	1/1977	Gaborieau et al.
4,023,607 A	5/1977	Jensen et al.

FIG. 3 is a side elevational view thereof rotated 90 degrees;

FIG. 4 is a side elevational view thereof rotated 270 degrees;

FIG. 5 is a side and top perspective view thereof;

FIG. 6 is a side and bottom perspective view thereof;

FIG. 7 is a top plan view thereof; and,

FIG. 8 is a bottom plan view thereof.

The broken lines are included for the purpose of illustrating boundaries of the invention and form no part of the claimed design.
